UTILITY CART FOR CONTAINERS AND THE LIKE

Harold J. McGrath, Royal Oak, Mich.

Application September 28, 1956, Serial No. 43,129

Term of patent 14 years

(Cl. D14—3)

Fig. 1.

Fig. 2.

Fig. 3.

Fig. 1 is a perspective view taken from above the cart embodying my new design.

Fig. 2 is a perspective view taken from the side.

Fig. 3 is a perspective view taken from the top and front, the broken line showing the utility cans being for the purpose of illustration only.

I claim:

The ornamental design for a utility cart for containers and the like, substantially as shown and described.
